UNITED STATES PATENT OFFICE.

OTTO L. WEIMAR, OF MANAYUNK, PENNSYLVANIA.

PIE-MARKER.

SPECIFICATION forming part of Letters Patent No. 771,192, dated September 27, 1904.

Application filed February 6, 1904. Serial No. 192,391. (No model.)

To all whom it may concern:

Be it known that I, OTTO L. WEIMAR, a citizen of the United States, residing at Manayunk, in the county of Philadelphia and State 5 of Pennsylvania, have invented a new and useful Improvement in Pie-Markers, of which the following is a specification.

My invention relates to a die and die-holder adapted to be used in marking pies 10 with an initial letter to designate the material of which the pie is composed, or the device may be employed to place on the pie any desired character or mark to designate the firm or company baking the pies so marked. 15 The device consists of the novel features of construction and combination of parts hereinafter described, particularly pointed out in the claims, and shown in the accompanying drawings, in which—

20 Figure 1 is a perspective view of my improved pie-marker. Fig. 2 is a perspective view showing the die-plate detached from the holder. Fig. 3 is a view showing the holder partly in end elevation and partly in 25 section, the die-plate being shown in position in section, the manner of removing the die-plate being shown in dotted lines.

In the drawings, A represents the die-holder, and B the die-plate. The holder A 30 comprises the sides A', the connecting top piece A'', and the parallel connecting-bars A''. Adjacent the lower edge of one of the side pieces A' and parallel to the said lower edge is a slot A⁴, and the opposite side piece is cut 35 away along the lower edge on the inner side, as shown at A⁵. To this last-mentioned side of the holder and adjacent the lower edge of same are secured on its outer face parallel lugs A⁶, between which are pivoted a spring- 40 actuated clamping member A⁷, one end of which projects over the lower edge of the side to which it is secured.

The die-plate B has formed on its under or front face the letter or other character B', 45 with which the pie is to be marked. One of the side edges of this plate is cut away on its front face, as shown at B², leaving a reduced portion adapted to fit in the slot A⁴. The opposite side of the die-plate is cut out on its 50 rear side, as shown at B³, leaving a marginal

portion of reduced width adapted to fit in the cut-out portion A⁵. It will be noted that the sides of the die-plate are therefore oppositely cut away. To place the die in the holder, the side having the cut-away portion B² is 55 placed in the slot A⁴, the upper end of the clamp A⁷ is depressed, and the remaining side of the die-plate is fitted into the cut-out portion A⁵ of the holder and the clamp released, thus locking the die-plate in position. 60

A handle A⁸ is carried by the top piece A'', and the manner of using the device will be obvious.

The die-plate is prevented from horizontal movement by reason of the fact that the cut-out portion A⁵ and the slot or recess A⁴ both stop short of the ends of the holder or the vertical edges of the side pieces. 65

Having thus fully described my invention, what I claim as new, and desire to secure by 70 Letters Patent, is—

1. A device of the kind described comprising a holder having parallel sides, one of said sides being longitudinally recessed on its inner face adjacent its lower edge and the other 75 side being cut away along the lower edge on its inner face, a die-plate adapted to fit between the lower edges of the said sides, and a clamp carried by the side cut away along the lower edge, said clamp being adapted to 80 project over the said edge and hold the die-plate in position.

2. A device of the kind described comprising a die-holder having two parallel side pieces, one of said side pieces having a recess 85 formed in its inner face adjacent and parallel to its lower edge and the other side piece being cut away along the lower edge intermediate its ends and on its inner face, a spring-actuated clamp secured to the outer face of 90 the last-mentioned side piece and adapted to project over the lower edge of the said side piece, and a die-plate oppositely cut away on the sides and adapted to fit between the lower edges of the said side pieces, substantially as 95 and for the purpose set forth.

OTTO L. WEIMAR.
